UNITED STATES PATENT OFFICE.

MARION MACMILLAN, OF NEW YORK, N. Y.

MILK-CAN.

1,234,189.

Specification of Letters Patent.

Patented July 24, 1917.

Application filed March 5, 1913, Serial No. 752,038. Renewed September 29, 1913. Serial No. 792,488.

To all whom it may concern:

Be it known that I, MARION MACMILLAN, a subject of the King of Great Britain, a resident of the borough of Manhattan, city, 5 county, and State of New York, have invented certain new and useful Improvements in Milk-Cans, of which the following is a specification.

The main object of this invention is to 10 provide a simple and efficient means for sealing the top or open end of a milk can by means of a moisture-proof closure and to protect said closure by means of a metal cover. The metal cover is so constructed 15 that it assists in holding the seal rigidly in position and protects the same from all damage either from causes outside of the can, or from the weight of the milk in the can, should the can be sufficiently inclined or be inverted, thereby bringing the weight of the 20 milk against the moisture-proof seal.

Another object of the invention is to provide a metal cover with a sealing flange adapted to tightly fit an upstanding neck 25 or throat carried by the can, and to provide an interlocking means by which these two parts may be securely locked together so that the said cover flange will form a dust-proof outer seal for the can.

Another object of the invention is to so 30 construct the upper end of the can throat or neck that the moisture-proof seal may be placed thereover and securely attached thereto and at the same time permit the cover 35 sealing flange to fit closely around the upstanding neck. To accomplish this the upper end of the neck is reduced in diameter to form an inwardly extending annular shoulder and the upper end of the reduced 40 portion is beaded on its outer side to form a flange under which the sealing cover may be forced and secured by an annular tie device.

Another object of the invention is to provide the cover on its under side with a cap 45 having a flat upper wall, the downwardly extending part of this cap forming the cover flange. The flat upper wall of this cap is adapted to contact with and to protect the entire seal across the top of the can neck so that said seal will be backed with a rigid supporting surface, thereby effectively preventing any breaking or rupture of said seal either through the careless handling of 50 the can or by the weight of the contents of the can being brought thereon.

In the drawing, Figure 1 is a plan view of the can with the cover detached and inverted;

Fig. 2 a vertical central sectional view 60 of the can with the cover in position thereon;

Fig. 3 a detail perspective view of the can seal detached and inverted;

Fig. 4 a detail vertical sectional view of the can neck showing the can provided with 65 a lining and the seal in position thereon;

Fig. 5 a detail side elevation of a portion of the can neck and the cover flange, showing the interlocking means; and

Fig. 6 a detail sectional view on an enlarged scale of a portion of the cover and the can neck interlocked.

Referring to the various parts by numerals, 1 designates the can body and 2 the upwardly extending contracted neck or 70 throat thereof. The upper end of this neck is reduced in diameter, at 3, to form the inwardly extending shoulder 4; and the upper end of this reduced portion is formed into an exterior annular bead or flange 5. 75 Extending over the open upper end of the neck is a seal 6 which is preferably formed of moisture-proof and impervious material, such as paper properly treated, or any other suitable material. This seal is bent around 80 the bead 5 and terminates approximately on the shoulder 4. A suitable tie wire or band 7 is then secured in position around said seal, said wire drawing the seal inwardly under the bead 5 and preventing the upward 85 withdrawal of the seal. This sealing wire or band, or other device, is permanently and rigidly secured in position so that it can not be removed without breaking it. The part 3 of the neck is sufficiently reduced in diameter to permit the seal and the securing band to be placed thereover without projecting 90 outwardly beyond the outer surface of the neck 2, as shown clearly in Fig. 6, and for a purpose which will be hereinafter 95 described.

The cover 8 is provided on its inner side with a cap 9 formed with an annular depending cover flange 10. The upper wall 10^a of this cap is flat, or smooth and is 105 adapted to directly contact with the seal 6 and to support the seal throughout its entire upper surface. This upper wall of the cap also forces the seal into direct and close contact with the surface of the bead 5, the 110 corner formed by the junction of the cover flange 10 with the upper wall 10^a of the

cap fitting approximately against the seal and forcing the same into contact with the bead 5, as shown clearly in Figs. 2 and 6.

The cover flange 10 of the cap fits snugly 5 against the exterior surface of the neck 2 and forms a dust-proof protection for the seal and prevents the accumulation of dirt or dust in the space formed by the reduced portion 3 of the neck. This flange also 10 protects the seal wire or band 7 and completely covers the seal so that it cannot in any way be injured without the complete removal of the cover. The neck 2 is formed at suitable points with outwardly extending lugs 11; 15 and the cover flange 10 is provided with vertical channels 12 adapted to receive said lugs when the cover is placed in position over the neck. The flange 10 is formed with slots 13 which open into the channels 12, the 20 lower wall of these slots inclining upwardly slightly as shown in Fig. 5. It is manifest that by placing the cover over the neck in such position that the lugs 11 register with the channels the said cover may be forced 25 downwardly to bring the wall 10^a of the cap into contact with the seal 6 and to bring the lugs 11 into register with the slots 13 of the cover flange. By then rotating the cover in 30 the proper direction the lugs 11 will engage the inclined lower walls 13^a of the slots and serve as cams to draw the cover downwardly and to lock it in contact with the seal. This will prevent the accidental disconnection of the cover from the can; and 35 the wall 10^a of the cap will so brace and support the seal 6 that it cannot be broken either through the careless handling of the can or through the weight of the material in the can being brought on said seal by undue tilting, or by upsetting the can.

If desired the can may be provided with a lining as shown at 15 in Fig. 4, this lining being carried upwardly and over the bead 5 on the neck, and the seal 6 being then placed 45 in position over the edge of the lining and tied in place, thereby securely holding the upper edge of the lining.

The cover is preferably permanently connected to the can body by means of a strong 50 chain 16 so that it cannot be wholly disconnected from the can. The tie wire or

band 7 is to be of any suitable material which when broken could not be again used, thereby indicating whether or not the contents of the can had been tampered with 55 after it was originally sealed.

What I claim is:

1. A liquid-tight receptacle comprising a can provided with a neck the upper edge of which is rolled to form an external bead, 60 said beaded upper edge being of less diameter than the body portion of said neck, a flexible moisture seal extending across the mouth of the can and having its edges terminating below said external bead, a sealing band confining the edge of said seal beneath said bead, and a cover having a flat central portion extending entirely over the mouth of the can in contact with said moisture seal, said cover being formed with a 65 depending annular flange inclosing the moisture seal and sealing band and closely fitting the body portion of the can neck below said bead and sealing band.

2. A liquid-tight receptacle comprising a 70 can provided with a neck the upper edge of which is rolled to form an external bead, said beaded upper edge being of less diameter than the body portion of said neck, a 75 flexible moisture seal extending across the mouth of the can and having its edges terminating below said external bead, a sealing band confining the edge of said seal beneath said bead, and a cover having a flat 80 central portion extending entirely over the mouth of the can in contact with said moisture seal, said cover being formed with a 85 depending annular flange inclosing the moisture seal and sealing band and closely fitting the body portion of the can neck below 90 said bead and sealing band, and means for clamping the flat portion of the cover tightly upon the beaded edge of the can neck to support the flexible seal against outward pressure and form a liquid-tight joint 95 around the beaded edge of the neck.

In testimony whereof I hereunto affix my signature in the presence of two witnesses.

MARION MACMILLAN.
